UNITED STATES PATENT OFFICE.

MATTHEW T. CHAPMAN, OF AURORA, ILLINOIS, ASSIGNOR TO THE AMERICAN WELL WORKS, OF AURORA, ILLINOIS, A CORPORATION OF ILLINOIS.

MEANS FOR BORING WELLS.

1,420,365.

Specification of Letters Patent. Patented June 20, 1922.

Application filed October 28, 1918. Serial No. 260,044.

To all whom it may concern:

Be it known that I, MATTHEW T. CHAPMAN, a citizen of the United States, and a resident of Aurora, in the county of Kane, State of Illinois, have invented certain new and useful Improvements in Means for Boring Wells, of which the following is a specification, reference being had to the accompanying drawings.

10 This invention relates to improved means for boring wells. Frequently with the tools and apparatus as now generally employed for this purpose the boring of a deep and approximately perfectly straight hole is a matter very difficult of accomplishment owing to the varying character of the strata through which the bore is to be forced. By reason of certain of the strata that are encountered being hard on one side and soft 20 on the other, or filled with rocks, or being of varying inclinations, a single earth boring tool is apt to be deflected from a straight line, and such deflection not only causes great difficulty in further boring but makes it extremely difficult to properly install, as 25 is frequently necessary, a centrifugal pumping apparatus in the bore. It is the object of my invention to provide means that will in large measure overcome the difficulties 30 incident to the boring of an approximately vertical hole in the earth, and briefly stated, I accomplish this object by associating two members for the production of such bore, one of such members being in the form of 35 a cylinder or tube and the other member being a drilling tool of novel construction located in the cylindrical tube member. These two members while perfectly independent of each other with respect to their 40 being moved in a rotary manner and in a reciprocatory manner are also capable of being, and frequently will be, moved in either or both of such ways simultaneously. While the preferable construction of these 45 parts and the results produced by their separate or joint action will be described fully hereinafter, it should be here stated that each of them is so constructed as to engage and hold small hard particles of material so as 50 to utilize such hard particles as a medium for cutting into and wearing away the bottom and side walls of the bore being formed; and also it is here pointed out that the boring tool member located within the cylindrical or tube member is provided with an

extended flat bottom surface which bears with great weight over a large portion of the bottom of the bore, and by reason of such extended bearing surface and weight a very considerable friction is engendered 60 between such bottom surface and the bottom of the bore when such bottom of the bore consists of rocky material. Such friction between such two surfaces produces a very appreciable amount of heat and to the heated surface of the rocky formation water is conducted through an opening in the boring tool, and the result of such heating and application of water results in aiding the disintegration of the material so that it is more readily scraped or broken off by the tool in its rotation and more easily chipped and broken off when such tool is dropped upon it forcibly as is done from time to time. 75

In the drawings,—

Fig. 1 is a view of one embodiment of my improved boring means in a bore formed by said means,—the drilling tool member being in elevation and the cylinder or tube 80 that encloses the drill tool member being shown in longitudinal vertical section;

Fig. 2 is a perspective view of the drill tool member of the boring means;

Fig. 3 is a view of the drill tool member, 85 the body thereof being shown in elevation and the bit member partly in vertical section;

Fig. 3^a is a bottom view of the drill tool; and 90

Fig. 4 is a perspective view of the lower end portion of the cylindrical or tube member of the boring means.

Referring to the drawings—15 indicates the cylindrical or tube member of my improved boring means, which member 15 will be the lowermost one of a series of pipe sections coupled together in the usual manner. This member 15 is shown as provided exteriorly and interiorly with a large number 95 100 of longitudinally extending grooves or serrations, those on the exterior being indicated by 16 and those on the interior by 17. These grooves 16 may be of any desired depth or width and preferably, and especially when 105 made of some considerable depth, those on one surface will come opposite the spaces between adjacent grooves on the other surface, as clearly shown in Fig. 4, so as not to unduly weaken the tube. These grooves 110

16 and 17 are for the purpose of receiving and temporarily holding small particles of hard material which act as an abrading means when the tube is rotated to wear away 5 the surface of the bore being formed and the surface of the core that results from and fills the member 15 as the making of the bore progresses. Such wearing away of the material at these places produces an annular cutting in which the tubular member turns 10 and sufficiently large to permit such member to be freely drawn up and with comparative ease. In the lower part of the member 15 I also provide a plurality 15 of quite long slots 18 which are so formed as to extend in a diagonal direction with their lower ends considerably in the rear of their forward ends—the term forward and rear being used relatively to the direction in 20 which the member 15 will be rotated. In all boring operations it is necessary, of course, to furnish water under pressure to the bottom of the bore and with the boring member 15 projected further into the material being bored through than is the other 25 boring member that will be hereinafter described the water will pass from such other boring member down through the interior grooves 17 to these large inclined slots 18, 30 and will thereby be directed against the wall of the bore near its lower end. Furthermore, these slots, as shown in Figs. 1 and 4, will receive at various points in their length pieces of hard gritty substances that 35 are made use of as an abrading element, and, in conjunction with the similar but smaller pieces of such substances that lodge in and are carried by the vertical grooves in the member 16, tend to wear away the wall 40 of the bore.

Referring now to the other member of the means that I employ for the boring of the hole, 19 indicates a drilling tool, the body of which is of materially greater width than 45 thickness so that it presents two substantially parallel flat faces. The general shape of the body of this tool is best shown by the perspective view of it shown in Fig. 2, and the bottom view shown in Fig. 3^a. The 50 side edges of the body are curved to properly correspond to the cylindrical form of the member 15 in which this tool member 19 is located. From opposite faces of the body of the boring tool project two lateral extensions 55 20, the extension that projects from one face being at the opposite side of the tool from the extension on the opposite face. Each of said extensions has its outer edge curved so as to form a continuation of the 60 curved edge of the body of the tool, and the upper face of such extension is quite sharply curved or inclined. These extensions may be of any height desired, but I prefer to make them so that their upper ends approach 65 the upper part of the body of the

tool, and this for the reason that as the flat lower faces of the extensions and the body wear away, as they will in use, there will still be preserved a comparatively sharp cutting edge at the juncture of such flat face 70 of the extension with its inclined upper face. While such comparatively sharp edges are thus preserved during the life of this member 19 it is to be understood that such edges are not relied upon in practice for actually 75 cutting or shearing off the material through which the well-bore is being made, but rather the function performed by such edges is to cut into and stir up the loosened material at the bottom of the hole, such material being then directed up over the said edge portions, and, with the water which is as usual forced under pressure down through the boring pipe hereinafter mentioned, will pass up the inclined faces of the 80 said extensions 20. The higher the extensions are made the longer will be the life of the tool. In the drawings the sharp cutting edge referred to is indicated by 21 (see Fig. 2). In the construction shown, and with a 90 new tool, the width of the extensions will ordinarily be such that their cutting edges 21 will extend somewhat past the vertical axis of the tool. It will be evident that as the boring tool is rotated in the direction 95 to make effective use of the cutting edges the loose material scraped or ground off of the bottom of the bore being made will, as before stated pass up the inclined surfaces of the extensions, and as much of such material is of the very hard gritty character hereinbefore referred to I provide means for catching some of such small particles and utilizing them to act as an abrading or 100 wearing means between the bottom of the 105 bore being made and the under face of the rotary tool 19. Such means consist of a number of openings 22 which, as best shown in Fig. 3, extend diagonally through the extensions and thus conduct such particles to the bottom of the tool in the rear of the cutting edges 21. Through these holes will also 110 pass some of the water that is fed downward through the tool, as hereinafter explained, such water serving to force the gritty substances through the holes and underneath the drill. As many of these holes 22 may be provided through the extensions as desired. In the outer surfaces of the extensions I 115 also provide a number of grooves 23 which are also inclined in substantially the same direction as the holes 22. These grooves extend from the inclined faces of the extensions to the bottom faces, and, as best shown in Fig. 2, such grooves are of tapering form 120 with their larger ends opening into the inclined surfaces. Through these tapered grooves will also pass small particles of the hard or gritty substances referred to which will be retained therein for a considerable 125 130

time and by reason of their projection beyond the curved faces of the extensions they will act as an abrading or wearing medium and cause a wearing away of the wall of the bore being made when the tool 19 is projected below the open lower end of the tube member 15, as at times is the case. In time these particles so caught will be so reduced in size that they will pass down and out of the grooves and be further crushed and mixed with the muddy water in the bottom of the bore and be carried away as such water is forced out in the usual manner. The upper end of the tool 19 is provided with a screw-threaded nipple 24 by means of which the tool is securely connected through a coupling 25 with the lower end of a pipe 26 by which the tool is supported and rotated, and through which is also supplied under pressure a continuous flow of water which passes through the nipple into a passage 26^a that extends centrally through the body of the tool. Below the nipple there are also provided two lateral openings 26^b, one at each side, which communicate with the central opening 26^a so that a portion of the water may be discharged through them and against the material on the inclined faces of the extensions.

It is to be understood that the upper end of the string of pipe sections 26 and the upper end of the string of cylinders or tubes of which the member 15 is the lowermost one will be connected with suitable mechanism adapted to impart to the two strings both a rotary and a reciprocating motion, and that either string may be rotated or reciprocated simultaneously with or independently of the other string. I have not deemed it necessary to illustrate any such elevating or reciprocating mechanism as mechanism for such purposes is well-known, and any usual construction for such purpose may be employed.

In the operation of the drilling means comprising the two principal members 15 and 19 the character of the strata encountered will often require that for the best results the tubular member 15 be rotated so that it projects down at some little distance below the tool member 19. So forcing it ahead of the tool member will leave, as shown in Fig. 1, a core of material to be operated upon by the drill member. The formation in this manner of a core of material enables the tool member to do more rapid and effective work where the material of the core is of a very hard character because when in core shape such material will be more readily broken and disintegrated by the tool than if such tool were operating on the material in its original condition. It will be understood that, as is usual, a stream of water will be constantly forced down to the bottom of the bore, as hereinbefore described, and will not only wash away the debris but will carry

small particles thereof into position to lodge in the openings and slots 22 and 23. Furthermore, such water coming upon the surface of the hard material that has been appreciably heated by the great friction between the lower face of the tool and the bottom of the bore will assist in crumbling and cracking the hard material of the bore so as to render its removal to be more readily effected. It will also be understood that in addition to the rotary movement imparted to the tool 19 such tool will be from time to time raised and allowed to drop with great force to further aid in cracking and crushing the material being operated upon.

I have spoken of the small hard particles that are broken from the material being removed being used as the abradant that is caught and held in the various slots, openings and passages of the two members of the boring means, and such material in many instances will be found very satisfactory for the purpose, but under some circumstances, as when passing through strata of a character not adapted for furnishing such small hard particles, I contemplate supplying such abrading material in the required quantity by dropping it from above through the pipe 26 that carries water under pressure to the bottom of the bore, and when so supplied such material may be in the form of chilled shot, crushed steel, or other small particles of any gritty substances, such as granite, emery, glass or sand.

By the use of my improved system of boring means comprising a tool having a flat bottom face rotated in a deep well by a long line of boring pipes weighing thousands of pounds, a high degree of heat is developed between the tool and the walls of the bore, serving to scorch the rock at the bottom of the bore, and cause it to flake off or buckle outward on the face so as to be torn off by the tool. This flaking and cracking of the rock is very materially aided, moreover, by the contact of the cold water with the heated rock whereby a very effective operation is attained by reason of the friction of the drill and the action of the cold water upon the heated surface quite independently of the action of the abrading particles. By my provision of a single structure embodying all of the above-described features,—comprising the development of a high degree of heat by the use of a flat-bottomed tool, the directing of the cold water upon the heated bottom face of the bore, and the use of the means for carrying around with the tool the hard particles of the abrading material,—I have been able to attain highly satisfactory results.

What I claim as my invention and desire to secure by Letters Patent, is—

1. A rotary boring tool comprising a body portion of materially less thickness than

- width and two extensions at the lower end of the body, said extensions projecting from opposite faces of the body and at opposite sides of said faces, each of said extensions being provided with passages for conducting small hard pieces of material below the lower faces of said extensions. 5
2. A rotary boring tool comprising a body portion of materially less thickness than width and two extensions at the lower end of the body, said extensions projecting from opposite faces of the body and at opposite sides of said faces, each of said extensions having inclined upper faces and flat lower faces, said extensions having cutting edges and each having means for conducting small hard particles below their lower faces. 10
3. A rotary boring tool comprising a body portion of materially less thickness than width and two extensions at the lower end of the body, said extensions projecting from opposite faces of the body and at opposite sides of said faces, each of said extensions having inclined upper faces and flat lower faces, each of said extensions having a cutting edge and each having inclined passages for conducting small hard particles below their lower faces and in rear of said cutting edges. 15
4. A well-boring drill comprising a body portion of materially less thickness than width and two extensions at the lower end of the body, said extensions projecting from opposite faces of the body and at opposite sides of said faces, each of said extensions having a smooth lower surface approximately perpendicular to the longitudinal axis of the body, an inclined upper surface and a curved periphery, said extensions each having passages for conducting small particles of abrasive material from said inclined surfaces to and below said bottom surfaces. 20
5. A rotary boring tool, comprising a body portion of materially less thickness than width, and an extension projecting from one face of the body at one side thereof, said extension being provided with passages for conducting small particles of abrasive material below its lower face. 25
6. A rotary boring tool comprising a body portion of materially less thickness than width and two extensions at the lower end of the body, said extensions projecting from opposite faces of the body and at opposite sides of said faces, each of said extensions being provided with passages for conducting small hard pieces of material below the lower faces of said extensions, said lower faces being broad and flat to cause when rotated a heating by friction of the hard material in the bore being formed, in combination with means for supplying water to such material to cause a more rapid disintegration thereof. 30
7. A rotary boring tool comprising a body portion and extensions at the lower end of the body, said extensions projecting from opposite faces of the body and at opposite sides of said faces, each of said extensions being provided with passages for conducting small hard pieces of material below the lower faces of said extensions. 70
8. A rotary boring tool comprising a body portion and extensions at the lower end of the body, said extensions projecting from opposite faces of the body and at opposite sides of said faces, each of said extensions having inclined upper faces and flat lower faces, said extensions having cutting edges and each having means for conducting small hard particles below their lower faces. 75
9. A rotary boring tool comprising a body portion and extensions at the lower end of the body, said extensions projecting from opposite faces of the body and at opposite sides of said faces, each of said extensions having inclined upper faces and flat lower faces, each of said extensions having a cutting edge and each having inclined passages for conducting small hard particles below their lower faces and in rear of said cutting edges. 80
10. A well-boring drill comprising a body portion and extensions at the lower end of the body, said extensions projecting from opposite faces of the body and at opposite sides of said faces, each of said extensions having a smooth lower surface approximately perpendicular to the longitudinal axis of the body, an inclined upper surface and a curved periphery, said extensions each having passages for conducting small particles of abrasive material from said inclined surfaces to and below said bottom surfaces. 85
11. A rotary boring tool comprising a body portion and an extension projecting from the lower end of the body at one side thereof, said extension being provided with passages for conducting small particles of abrasive material below its lower face which is broad and flat to cause when rotated a heating by friction of the hard material in the bore being formed, in combination with means for supplying water to such material to cause a more rapid disintegration thereof. 90
12. A rotary boring tool comprising a body portion and extensions at the lower end of the body, said extensions projecting from opposite faces of the body and at opposite sides of said faces, each of said extensions being provided with passages for conducting small hard pieces of material below the lower faces of said extensions, said lower faces being broad and flat to cause when rotated a heating by friction of the hard material in the bore being formed, in combination with means for supplying water to such material to cause a more rapid disintegration thereof. 95
